UNITED STATES PATENT OFFICE

CHARLES INNESS BROWN, OF QUEENS VILLAGE, NEW YORK

LAMP

Application filed July 29, 1930. Serial No. 471,443.

This invention relates to electric lamps, particularly to table lamps, especially suitable for use on dressing tables or elsewhere, where a soft light is desired.

The principal object of the invention is to provide a lamp of this type of simple construction permitting easy assembly and replacement of the bulb or other parts and which shall give, when lighted, a substantially uniform glow from its various portions.

I have found in accordance with my invention that a lamp having a translucent base such as semi-opaque glass and a shade fitted thereover of like material with an electric bulb positioned about centrally inside to illuminate equally the base and the shade, will produce such a substantially uniform glow when lighted.

The invention accordingly comprises the novel devices and combinations thereof, specific embodiments of which are described herein by way of example only and in accordance with the manner in which I now prefer to practice the invention.

The invention may be more clearly understood by reference to the accompanying drawing in which Fig. 1 is a perspective view of a lamp made in accordance with my invention; Fig. 2 is a vertical central section of the lamp; and Figs. 3 and 4 are vertical central sections of modifications of the lamp structure.

Referring now to the drawing, the numeral 1 represents a hollow cylindrical base of said translucent material here preferably shown as semi-opaque glass. The base has a narrowed cylindrical integral neck portion 2 projecting from the upper portion thereof. 3 designates a conical removable shade also preferably made of the same hard translucent material such as semi-opaque glass and provided with a narrowed downwardly extending cylindrical integral neck portion 4 fitting about the neck portion 2 and supported on the flat shoulder which extends between the neck and the body of the base. As herein shown the visible portions of the shade and base including the neck portion of each have substantially the same light-transmitting properties. Together the shade and base

make preferably a completely enclosed lamp in which preferably an electric bulb 5, constituting the source of light for the lamp, is situated. The bulb is supported in a socket 6 mounted on a screw-threaded stem 7 which passes through an aperture in the concave base 8. Washers lie about this stem 7 on the upper and lower sides respectively of the base 8 and a nut 10 holds the various parts assembled in fixed position. Current is supplied to the bulb through wiring 11 passing through an aperture in the side of the base 1. The concave base permits the supporting means for the socket to be raised above the lower extremity of the base so that the lower edge of the latter sits directly on the table or other support.

The bulb 5 is here shown as provided with a substantially circular filament 12 which is located about centrally of the lamp preferably within the necks 2 and 3.

The lamp shown in Fig. 1 is provided with a detachable plug 13 and switch 14.

When current is supplied to the bulb 5, the light from the filament which as shown is about in the center of the lamp, is shed about equally to the various parts of the lamp and the light is accordingly diffused with about equal intensity from the various parts of the lamp. There is thus produced a beautiful softly glowing effect from the shade, the neck and down to the lower edge of the base.

In Fig. 3 a somewhat modified lamp body is shown. The base and shade here are made up of parts which resemble a spade in cross section. The base or stem of the spade 15 has a short cylindrical neck 16. The upper portion 17 of the spade has an aperture fitting over the neck 15, the wall 18 adjacent the aperture lying on the flat shoulder 19 between the neck and the stem 15. In Fig. 4 a globular base 20 is shown with a somewhat flattened conical shade. The lamp 5 in this instance is supported by means of the stem 7 which projects through an aperture in the upper flattened surface of a truncated cone 21 molded to project inwardly from the base 20 as shown in Figs. 3 and 4. It will be noted that the filament 12 in each of the bulbs in Figs. 3 and 4

is located about the center of the lamp so that the light shed to the various parts of the lamp is diffused with about equal intensity from those parts. The shade and base in each of these figures is preferably made of translucent semi-opaque glass.

The light passing through the shade and base when diffused is of about equal intensity from all portions of the lamp above the lower-most edge of the base. Since this edge rests on the table or the support light such as passes through the bottom of the base will not be directly seen. Due to the presence of the socket above the bottom of the base, of course the light passing through this bottom will not be of uniform intensity when such a socket is used.

In the claims where I use the expression "supported directly thereby" in referring to the support of the shade by the base, I mean that the base supports the shade without any intermediate metal or other material of a non-translucent character.

It will be understood that the lamp may take other forms than as herein shown. I may use other material than semi-opaque glass. It is preferable, as indicated, that the base and shade completely enclose the source of light and that each of them be made of translucent material preferably having about the same light-transmitting qualities. I prefer to have the construction as simple as possible by providing the neck portion about which the upper part or shade of the lamp is supported and am able to do away with other more complicated supporting means and at the same time to preserve the desired light diffusing characteristics of the lamp. By making the body and shade of hard self-sustaining material such as glass, I am also able to do away with ribs and like sustaining means for the base and shade and therefore to preserve the light-transmitting characteristics of these parts throughout.

What I claim as new and desire to secure by Letters Patent is:—

1. A lamp having a separable light diffusing glass base and shade, said base comprising a hollow body with substantially vertical side walls terminating at the upward ends in a substantially horizontal inwardly directed ledge having an upstanding flange protruding from the inner edge thereof, said shade comprising a hollow body having at its lower end an inwardly directed substantially horizontal portion adapted to form a support for said shade upon said ledge, an incandescent light positioned within said flange and being of smaller diameter than said flange, whereby said incandescent light transmits direct light to substantially all interior surfaces of said walls and shade to give a substantially uniform glow to all visible parts of the lamp.
2. A lamp according to claim 1 in which the

substantially horizontal support for the shade has a vertical flange whose lower edge rests on the ledge.

In testimony whereof I have signed my name to this specification.
